UNITED STATES PATENT OFFICE.

NATHAN I. DRYFOOS, OF CLEVELAND, OHIO.

SWEATER.

Application filed February 18, 1922. Serial No. 537,633.

To all whom it may concern:

Be it known that I, NATHAN I. DRYFOOS, a citizen of the United States, and a resident of Cleveland, county of Cuyahoga, and 5 State of Ohio, have invented a new and useful Improvement in Sweaters, of which the following is a specification, the principle of the invention being herein-explained and the best mode in which I have contemplated 10 applying that principle, so as to distinguish it from other inventions.

The present invention relates to sweater construction, and more particularly, to the construction of the collar which allows the 15 same to lie flat over the shoulders, to be used as a double short stand-up collar, or to be completely extended to cover the head of the wearer. Provision is also made for securing it in its raised position; a strap being employed which lies flat between the folds of the collar in the intermediate position so as to be out of sight. To the accomplishment 20 of the foregoing and related ends, said invention, then, consists of the means herein-25 after fully described and particularly pointed out in the claim.

The annexed drawing and the following description set forth in detail certain mechanism embodying the invention, such disclosed means constituting, however, but one 30 of various mechanical forms in which the principle of the invention may be used.

In said annexed drawing:—

Fig. 1 is a front elevational view of a 35 sweater showing the collar in its lowered position; Fig. 2 is an elevational view, slightly from the side, showing the collar in its intermediate position; Fig. 3 is a side elevational view showing the collar in its raised 40 position with the strap in place; Fig. 4 is a sectional view on the line 4—4 of Fig. 2; and Fig. 5 is a diagrammatic plan view of the upper portion of the sweater and of the 45 collar to show the form of neck opening, the manner of making the same, and the collar before attachment.

The present sweater is of the slip-over 50 type having the usual body 1 and arms 2 with a neck opening 3, which is formed by making a rectangular notch in the front portion of the garment. This notch or square opening as shown in Fig. 5 is formed by dropping a number of stitches 20, sixteen such 55 stitches being shown as dropped to make the lower edge 21 of the neck opening, and then knitting nine more rows on each side 22.

The back is knitted full all the way up leaving an opening of a total of fifty stitches, sixteen top and bottom and nine on each side. To this neck opening is attached a 60 collar 4 which is merely a rectangular strip of knitted material as shown in Fig. 5 having as many rows of stitches as there are stitches around the neck opening, or fifty such stitches in the present illustration. 65 This collar is then sewed to the neck opening stitch for stitch which shapes the neck opening as best shown in Figs. 1 and 2 and gives a slight amount of transverse fullness in front. This manner of attaching the collar 70 prevents the transverse wrinkle so common at the neck and also allows the collar to lie flat when in the turned down position shown in Fig. 1.

The collar is of course open at the front 75 and the edges 15 and 16 extend outwardly toward the shoulders. As shown, the collar is preferably formed in two colors, the dividing line being approximately half of the collar length so that when the collar is folded and raised to the intermediate position, the outer portion 5 shows the same color as the sweater body. The inner half of the collar is provided with buttons 6 and buttonholes 7 by which it may be secured 80 together in front to maintain it in its closed position as shown in Fig. 2. The flaring edges 15 allow the collar to fit snugly when in its raised folded position.

The collar may also be raised completely 90 into the position shown in Fig. 3 and in this position the collar is high enough to extend under the sides of a cap or hat if desired. The flaring edges of the outer half form a 95 V-opening in front in this raised position to fit around the chin of the wearer and to allow the collar to fit snugly against the cheeks of the wearer. A strap 8 is also provided which has button-holes 9 adjacent its ends and this strap may be passed over the 100 head of the wearer and secured to buttons 10 placed on the underside of the lower half of the collar where they are concealed when the collar is in the positions shown in Figs. 1 and 2. When in the position shown in Fig. 2, the strap lies between the folds of the collar fitting snugly around the back of the neck and is completely concealed.

This collar construction makes it possible 110 in a single sweater to approximate not only the usual sweater neck type of double construction as when used, as shown in Fig. 2,

but also to have the collar lie flat on the shoulders so as to allow the sweater to be used as a vest in place of the usual V-neck type as well as providing a high collar forming a neck and head covering which may be fastened and held in place by means of the strap. By sewing the straight edged collar to the squared neck opening the sweater bulges slightly at the front of the neck when 10 not being used, thus giving the necessary fullness when being worn and when the collar is raised into the position shown in Fig. 2 aiding in forming a close tight fitting military type of collar. With the features 15 mentioned a neat appearance is obtained at all times, the strap and buttons being normally concealed and lying flat so as not to wrinkle or bulge the collar in any position. This is accomplished with a neat appearance, 20 the strap and buttons therefore being normally concealed and lying flat so as to maintain the neat smooth appearance of the collar at all times.

Other modes of applying the principle of 25 my invention may be employed instead of the one explained, change being made as regards the mechanism herein disclosed, provided the means stated by the following

claim or the equivalent of such stated means be employed.

I therefore particularly point out and distinctly claim as my invention:—

In a sweater the combination of a body portion having a neck opening and a collar attached thereto adapted to be raised about 30 the ears and head, said collar being open at the front and formed with the front edges extending outwardly to leave a wide angle in its normal position, the inner half of the front edges being provided with complementary fastening means to secure the collar edges together to form a folded collar adapted to fit snugly about the neck of the user, the outer edges of the folded collar flaring slightly, and a strap removably attached to the under side of the outer half of the collar near the front and extending around the collar and adapted to lie flat between the folds in the folded position of 45 said collar but adapted to be passed over 50 the head of the wearer in the raised position of the collar.

Signed by me this 28th day of January, 1922.

NATHAN I. DRYFOOS.
